(57) **CLAIM**

The ornamental design for a digital dial gauge, as shown and described.

DESCRIPTION

FIG. 1 is a front, right-side, bottom perspective view of the digital dial gauge;

FIG. 2 is a front elevational view thereof;

FIG. 3 is a top plan view thereof;

FIG. 4 is a right-side elevational view thereof;

FIG. 5 is a left-side elevational view thereof;

FIG. 6 is a rear elevational view thereof; and,

FIG. 7 is a bottom plan view thereof.

The broken lines depict boundaries of the claimed subject matter or are directed to environment and are for illustrative purposes only. The broken lines form no part of the claimed design.
